CLAIM

An ornamental design for a case with metal back and framed front for a cord management system, as shown and described.

DESCRIPTION

The present application relates to U.S. Design patent application Ser. No. 29/378,110 filed Oct. 29, 2010, entitled Case with Metal Back and Framed Front for a Cord Management System, and to U.S. Design patent application Ser. No. 29/378,118 filed Oct. 29, 2010, entitled Case with Metal Back and Framed Front for a Cord Management System. The present application also relates to U.S. Design patent application Ser. No. 29/377,918 filed Oct. 27, 2010, entitled Case with Combined Metal and Plastic Back for a Cord Management System, and to U.S. Design patent application Ser. No. 29/377,919 filed Oct. 27, 2010, entitled Case with Combined Metal and Plastic Back for a Cord Management System, and to U.S. Design patent application Ser. No. 29/377,921 filed Oct. 27, 2010, entitled Case with Combined Metal and Plastic Back for a Cord Management System, and to U.S. Design patent application Ser. No. 29/376,257, filed Oct. 4, 2010; U.S. Design patent application Ser. No. 29/376,428 filed Oct.

6, 2010, entitled Case with Metal Back and Band Edge for a Cord Management System, and to U.S. Design patent application Ser. No. 29/376,430 filed Oct. 6, 2010, entitled Case with Metal Back and Band Edge for a Cord Management System. The present application also relates to U.S. Design patent application Ser. No. 29/375,648, entitled Case with Metal Back for a Cord Management System, filed Sep. 24, 2010, and to U.S. Design patent application Ser. No. 29/375,649 filed Sep. 24, 2010, entitled Case with Metal Back for a Cord Management System, and to U.S. Design patent application Ser. No. 29/375,651 filed Sept. 24, 2010, entitled Case with Metal Back for a Cord Management System, and to U.S. Design patent application Ser. No. 29/376,041 filed Sep. 30, 2010, entitled Case with Metal Back for a Cord Management System, the disclosures of which are all incorporated herein by reference in their entirety.

FIG. 1 is a back perspective view of our new design of a case with metal back and framed front for a cord management system;

FIG. 2 is a back perspective view of another embodiment of our new design of a case with metal back and framed front for a cord management system;

FIG. 3 is a back perspective view of yet another embodiment of our new design of a case with metal back and framed front for a cord management system;

FIG. 4 is a first side view of the embodiments of FIGS. 1-3; FIG. 5 is a second side view of the embodiment of FIG. 1; FIG. 6 is a second side view of the embodiment of FIG. 2; FIG. 7 is a second side view of the embodiment of FIG. 3; FIG. 8 is a top side view of the embodiments of FIGS. 1 and 2;

FIG. 9 is a top side view of the embodiment of FIG. 3;

FIG. 10 is a bottom side view of the embodiments of FIGS. 1 and 2;

FIG. 11 is a bottom side view of the embodiment of FIG. 3; FIG. 12 is a back view of the embodiments of FIGS. 1 and 2; FIG. 13 is a back view of the embodiment of FIG. 3;

FIG. 14 is a front perspective view of any of the embodiments of FIGS. 1-3, provided for illustrative purposes;

FIG. 15 is a front view of the embodiments of FIGS. 1 and 2; FIG. 16 is a front view of the embodiment of FIG. 3;

FIG. 17 is a front perspective view of any of the embodiments of FIGS. 1-3, illustrating these embodiments used in conjunction with an object;

FIG. 18 is a back perspective view of any of the embodiments of FIGS. 1-3, illustrating these embodiments used in conjunction with two objects;

FIG. 19 is a back perspective view of any of the embodiments of FIGS. 1-3, illustrating these embodiments used in conjunction with three objects;

FIG. 20 is another back perspective view of any of the embodiments of FIGS. 1-3, illustrating these embodiments used in conjunction with three objects;

FIG. 21 is an exploded back perspective view of the embodiment of FIG. 1;

FIG. 22 is an exploded back perspective view of the embodiment of FIG. 2; and,

FIG. 23 is an exploded back perspective view of the embodiment of FIG. 3.

The broken lines showing elements of the case with metal back and band edge for cord management system in the above described Figures are for illustrative purposes only and form no part of the claimed design.
